UNITED STATES PATENT OFFICE.

STANLEY ROBERT WRIGHT, OF RAWDON, NEAR LEEDS, ENGLAND, ASSIGNOR TO
IGRANIC ELECTRIC COMPANY, LIMITED, OF LONDON, ENGLAND, A CORPORA-
TION OF GREAT BRITAIN.

COIL-WINDING MACHINE.

Application filed August 22, 1921. Serial No. 494,412.

(GRANTED UNDER THE PROVISIONS OF THE ACT OF MARCH 3, 1921, 41 STAT. L., 1312.)

To all whom it may concern:

Be it known that I, STANLEY ROBERT WRIGHT, a subject of the King of Great Britain, and resident of Rawdon, near 5 Leeds, Yorkshire, England, have invented certain new and useful Improvements in and Connected with Coil-Winding Machines (for which I have obtained a patent in Great Britain dated July 3, 1919, No. 153,350), of

10 which the following is a specification.

This invention relates to coil winding machines in which is provided means operating at recurring intervals when winding a cone, for progressively shortening and then 15 progressively lengthening the traverses of the thread or cotton guide from one end of the cone. This foreshortening of the cotton traverse has hitherto been effected by gradually varying the inclination of a normally 20 angular guide by means of a cam path which engages a roller carried by one arm of a bell crank lever, the other arm operatively engaging the cotton guide.

The object of the present invention is to 25 provide improved means of the above character which is capable of ready application to a standard plain coil winding machine to enable such machines to be used for the winding of conical coils and wherein the variation in the traverse of the cotton guide is 30 effected directly by the movement of the wire guide.

The means according to this invention for 35 progressively shortening and then progressively lengthening the traverse of the cotton guide comprises a bell crank lever the extremity of one arm of which is operatively connected to the cotton guide whilst the extremity of the other arm slides within a slot- 40 ted link which is pivoted and so connected to the wire guide as to be turned about its pivot consequent upon the traversing movement of said wire guide so as to cause said slotted link to gradually tilt to an angular 45 position and as gradually turn again to a horizontal position.

In order that the invention may be clearly understood, the same will now be described by aid of the accompanying drawings in 50 which:—

Fig. 1 is a front elevation of the essential

mechanism of a coil winding machine according to this invention.

Fig. 2 is an end view of the same.

Fig. 3 is a fragmentary rear elevation of 55 Fig. 1.

Fig. 4 is a similar view to Fig. 1 but drawn to a larger scale and slightly in perspective so as to more clearly show the relative dispositions of the parts. 60

Fig. 5 is a section through a typical coil built up by a machine according to this invention.

Fig. 6 illustrates one form of coil wound upon a standard coil winding machine fitted 65 with the attachment according to this invention.

Figs. 7, 8, 9 and 10 illustrate four stages in the laying on of the cotton during the return traverse of the wire guide and representing full, three quarter, half and fully 70 foreshortened traverses respectively.

According to the practical embodiment of the invention shown in the drawing, the wire traverse guide 1 is reciprocated so that 75 the first pair of layers 8 of wire is laid the full length of the coil, the second pair of layers 9 at, say, two-thirds the length of the coil, the third pair of layers 10 at, say, one third the length of the coil, and the fourth 80 pair of layers 11 again at perhaps two-thirds the length of the coil. This completes one cycle, i. e. one revolution of the cam. The winding of a coil consists of completing a series of such cycles until the correct number of turns is obtained. The net result of 85 one cycle of the cam is thus:—

Two full length layers.

Four two-thirds length layers.

Two one-third length layers.

Consequently at the apex of the coil I have two layers, but at the base I have eight layers, and this proportion is maintained throughout the winding of the coil, see 90 Fig. 5.

To attain the desired irregularity of movement of the cotton traverse, the guides 12 and the cotton traverse member 16 which is reciprocated with a uniform amplitude are both slidably mounted upon slide rods 13 100 and 13^a respectively, the cotton guide straddling the top of the traverse member so that

each is capable of movement relative to the other. The connecting medium between the cotton guide 12 and the cotton traverse member 16 comprises a bell crank lever 17 which is pivoted at 18 to the extension 19 of the cotton traverse member 16. The apex 20 of this bell crank is provided with a loose roller or slide 21 upon its extremity which engages a vertical slot 22 formed in bracket 23 of the cotton guide. The extremity of the lower arm remote from pivot 18 is similarly provided with a roller or slide 24 with which it engages a slotted link 25. This link is rigidly mounted upon one end of a transverse pivot pin 26 indicated in perspective in Fig. 4 which is supported in bearings forming part of a bracket 26^a which in turn is clamped to a fixed part of the mechanism such as the stay rods 26^b. The slot 25^a in the link 25 is of such a length as to coincide with or exceed the full traverse of the cotton traverse lever.

Rigidly mounted upon the pivot pin 26 at the end opposite to that of the slotted link 25 so as to move angularly therewith is an arm 27, the extremity of which is engaged in a slot 28 in a bracket 29 attached to the wire traverse.

From the above, it will be obvious that the angular position of the slotted link 25 is determined by the horizontal position of the wire traverse. The proportioning of the parts is such that when the wire traverse has completed a maximum forward stroke the said slotted link 25 is horizontal as shown in Fig. 1, and that when said wire traverse has completed a backward stroke said slotted link is angularly inclined as shown in Fig. 4.

It will be further understood that the movement of the apex 20 of the bell crank lever 17 and therefore of the cotton guide 12 depends, in the first place, upon the movement of the cotton traverse member 16 and in the second place upon the angular disposition of the slotted link 25. Thus suppose for the moment, that the slotted link is stationary in the position illustrated in Fig. 1, and that the cotton traverse member is reciprocating, it is plain that the slot 25^a being parallel to the direction of movement of said cotton traverse member, the said bell crank lever 17 will follow the movement of said cotton traverse member without changing its angular disposition and therefore the apex 20 thereof and the cotton guide 12 will reciprocate with precisely the same amplitude of stroke as the cotton traverse member 16. If, however, the slotted link 25 be supposed stationary in the position illustrated in Fig. 4 while the cotton traverse member 16 is reciprocating, the movement of the apex 20 of the bell crank lever 16, and therefore of the cotton guide 12 may be considered as made up of two components, viz., a horizontal movement equal to the bodily displace-

ment of the bell crank lever owing to its attachment to the cotton traverse member by the pivot 18, and a movement having a horizontal component in the opposite direction owing to the angular movement of the bell crank lever about the pivot 18 caused by the angularity of the slotted link 25 in which the end of the lower arm of said lever opposite to said pivot slides. In other words, during any interval of time the total horizontal component of the movement of said apex 20 and the guide 12 is less than the horizontal movement of the cotton traverse member 16 and therefore the amplitude of reciprocation of the cotton guide 12 will be less than that of the cotton traverse member 16. It is of course quite obvious that for positions intermediate those shown in Figs. 1 and 4 the amplitude of reciprocation of the cotton guide is less than for the position of Fig. 1 and greater than for the position of Fig. 4.

In accordance with well known practice the cotton guide is reciprocated at a much higher speed than the wire guide (in the ratio of about two hundred reciprocations to one) and as heretofore stated the cotton traverse member 16 is reciprocated at a uniform amplitude equal to the maximum length of the coil. It therefore follows that during any one whole reciprocation of the wire guide, say a maximum reciprocation from the position of Fig. 4 to that of Fig. 1 and back again, the cotton guide will make about two hundred reciprocations—one hundred increasing in amplitude from a minimum in which the thread is very much foreshortened or built up on the cheek of the coil at the base end to a maximum in which it is being wound over the whole length of the coil, and another hundred correspondingly decreasing in amplitude to said minimum. During reciprocations of the wire traverse member and guide of less than the maximum, the slotted link 25 will be turned from the position of Fig. 4 to a position intermediate Fig. 4 and Fig. 1 and back again, and the cotton guide accordingly will make one hundred reciprocations increasing from the same minimum as before to a lesser maximum and another hundred correspondingly decreasing to said minimum, the adjustment of the cotton guide traverse being such that the amplitude of the reciprocations of the cotton guide are always sufficient to include in their range the portion of wire being momentarily wound on the coil, and therefore each layer of wire is effectively bound and covered with cotton before the wire guide commences its return stroke. By building up, as above described, the cotton on the cheek of the coil at the large end, each layer of wire is effectively prevented from slipping off the coil at said large end.

Fig. 9 illustrates the interweaving of the cotton and wire as effected on a standard

coil winding machine fitted with the attachment according to this invention in which y represents the cotton or yarn and w the wire. As will be seen the cotton is built up 5 at the large end of the coil as indicated at x so as to prevent the wire from slipping off such end.

Figs. 7, 8, 9 and 10 illustrate four stages 10 in the laying on of the cotton commencing from a full traverse as shown in Fig. 7 and terminating with the foreshortened traverse shown in Fig. 10. The cam employed in 15 traversing the cotton guide is of usual form as fitted on standard coil winding machines and as a consequence the particular conformation of the cotton winding shown is also of usual form and will therefore not be described in detail here inasmuch as the present invention consists solely in the 20 means employed for effecting the foreshortening of the cotton traverse.

What I claim and desire to secure by Letters-Patent is:—

1. In a coil winding machine having independently operated wire and cotton traverse 25 means for progressively shortening and then

progressively lengthening the traverses of the cotton guide in which the variation is effected directly by the movement of the wire guide.

2. In a coil winding machine having independently operated wire and cotton traverses means for progressively shortening and then progressively lengthening the traverses of the cotton guide according to claim 1 comprising a bell crank lever the extremity of one arm of which is operatively connected to the cotton guide whilst the extremity of the other arm slides within a slotted link which is pivoted and so connected to the wire guide 35 as to be turned about its pivot consequent upon the traversing movement of said wire guide so as to cause said slotted link to gradually tilt to an angular position and as gradually turn again to a horizontal position. 40

3. A coil winding machine according to claim 1 in which means are provided for varying the extent of the full or normal traverse of the cotton guide.

In witness whereof I affix my signature. 50

STANLEY ROBERT WRIGHT.
